UNITED STATES PATENT OFFICE.

ROBERT JACKSON PERRY, OF BRISTOL, TENNESSEE.

TOY CAMERA.

Application filed October 29, 1926. Serial No. 145,043.

This invention relates to a toy camera, the object being to play a practical joke upon the individual not knowing its construction and who is persuaded to take his own picture. The invention comprises a neatly covered box imitative of a kodak with a finder in one end to represent a scene on the upper glazed side, and a slide opened for the avowed purpose of focussing a picture, when mechanism will be released which will throw upward devices which will have a puncturing point to prod his hand. The victim of the joke will be invited to take his own picture, and in making an exposure will get several surprises. To these ends the invention comprises a prismatic rectangular box covered with imitation leather and a carrying handle with a piece of glass in the forward end of the top below which a mirror reflects the person looking in the same. In the top of the box is a slide carrying a pivoted puncturing device invisible when the lid is closed, but adapted to be projected through the opening when the lid is withdrawn. An auxiliary device is provided in the bottom held under tension by a latch, and, as the picture is being taken (presumably to open the shutter), a puncturing device is thrust rearwardly to surprise the operator and also a plunger released on simulating making an exposure.

The several features will be more fully described hereinafter and will be definitely indicated in the appended claim.

35 In the drawings:

Figure 1 is a part sectional view on a vertical plane through the box.

Figure 2 is a top plan view.

Figure 3 is an end view at the finder end.

40 Figure 4 is a vertical section on a plane passing through the finder.

Figure 5 is a sectional view on the plane 5-5 of Figure 4.

45 Figure 6 is a bottom plan view showing the trip for the release of one of the surprising features.

Figure 7 is a fragmentary end view of the rear end.

Referring now in detail to the drawings, 50 1 represents a rectangular prismatic box covered on the outside neatly with imitation leather simulating a kodak, in the front wall of which is a rectangular strip of glass

2 and behind which is placed a printed picture of a fool's head, as shown at 3, and above which is a simulated finder 6 with a mirror 6' in which an observer will see his own reflection. On the rear end of the top of the camera is a longitudinal slide 7 sliding in undercut grooves 9, 9^a in the end walls, as indicated in Figure 5, and its forward end is provided with a notch 10 which engages a leaf spring 11 when the slide is pushed home. On the under side of this slide is secured by a screw a flexible strip 12 loosely connected to a central portion of the snake carrying a short needle point in its mouth, and its rear end pivoted in a cross pin 13 secured in the walls of the box. Thus, when the slide 7 is pulled outward the strip 12 carries the snake upward and prods the finger of the operator. In the bottom of the box lies a plunger 14 concealed in an opening to which a pin 15' is secured projecting through the bottom wall. A slot 16 in the wall permits the plunger to be projected forward and a compression spring 17 is put under tension when the plunger is pulled back so that the pin 15' locks in a bayonet catch formed at its angular extremity, as shown at 18. A trip lever 19 is pivoted on the bottom of the box with its trigger accessible to the operator using the toy, and when pushed forces the pin 15 out of the angle in the slot, thus releasing the spring 17 and projecting the prod forward. On the rear of the box is pinned a split piece of the covering fabric 4, 5 concealing the opening of the prodding plunger 14.

Having thus described my invention, what I claim as new and desire to secure by Letters Patent is:

A trick camera with imitation finder on the forward end of the top, a mirror positioned beneath the finder to be visible there through, a concealed spring actuated plunger with a prick point at its front, said camera provided with a recess at the bottom, opening outward thru the rear wall, said plunger being normally positioned within said recess with the spring under tension and a latch accessible to the photographer for releasing the spring, said latch being simulative of a shutter in taking a picture.

In testimony whereof I affix my signature.

ROBERT JACKSON PERRY.
